Primary Examiner — Jack Reickel*Assistant Examiner* — Melvin L Davis(74) Attorney, Agent, or Firm — Walters & Wasylyna LLC(57) CLAIM

The ornamental design for a game controller, as shown and described.

DESCRIPTION

FIG. 1 is a front and top perspective view of a game controller in accordance with the present design;

FIG. 2 is a front and bottom perspective view of the game controller of FIG. 1;

FIG. 3 is a front view of the game controller of FIG. 1;

FIG. 4 is a rear view of the game controller of FIG. 1;

FIG. 5 is a right side view of the game controller of FIG. 1;

FIG. 6 is a left side view of the game controller of FIG. 1;

FIG. 7 is a top side view of the game controller of FIG. 1; and,

FIG. 8 is a bottom view of the game controller of FIG. 1. The broken lines in the drawings show environment that forms no part of the claimed design.
